CONTOURED PILLOW

Louis G. Kaskey and Mary J. Kaskey, Chicago, Ill.

Application September 22, 1948, Serial No. 50,456

3 Claims. (Cl. 5—337)

1
Our invention relates to pillows and has reference more particularly to a pillow which is specially shaped and contoured to conform to and cushion particular portions of a person's body, such as the neck and head, the middle of the back and various other portions of the body.

The pillow of this invention is adaptable for a wide variety of uses, by automobile drivers and passengers, by travelers on trains, planes, and buses, for use by office workers and invalids, and for use in the home, hospitals, clubs and wherever a person may desire greater comfort or support for some part of the body to which the pillow may be particularly suitable.

Primarily, this pillow is designed to accommodate a person's neck so as to cushion and support the neck and head comfortably when sitting, but it is also useful as a back pillow to provide cushioning and support across the waist-line and along the side portions of the back, and for many other purposes such, for example, as a leg or arm rest to support the leg or arm at selected places.

The principal objects of our invention are, to provide a simple and convenient pillow or cushion of such contour that it is specially adapted for a variety of cushioning purposes; to provide the pillow with a neck accommodating recess at the front between laterally spaced pillow ends which engage the neck in a manner to support a person's head more comfortably than previous neck pillows; to construct the pillow at the rear for substantial bearing engagement, with a seat back or the like, whereby the pillow holds a person's head quite firmly in upright position; to construct the pillow ends and the interconnection therebetween so that the cushion is of appropriate shape to support and cushion a person's back; to provide the pillow in such shape and with suitable bearing engagement at the rear for upright positioning of the pillow ends so that it is adapted to serve as an effective and comfortable cradle support for various parts of the body, such as parts of the legs or arms; to provide a rear bearing engagement of the pillow which effects a rocking action of the pillow ends for holding body parts quite snugly in the front recess of the pillow; and in general to provide a neat, compact and attractive pillow which may be readily manufactured and has a wide range of utility—these and other objects being accomplished as pointed out more fully hereinafter and as shown in the accompanying drawing, in which:

Fig. 1 is a top plan view of a pillow embodying our invention;

Fig. 2 is a cross sectional view on the line 2—2 of Fig. 1; and

Fig. 3 is a view similar to Fig. 1 showing a modified form of our pillow.

2
Fig. 2 is a cross sectional view on the line 2—2 of Fig. 1; and
Fig. 3 is a view similar to Fig. 1 showing a modified form of our pillow.
5 As shown in the drawing, our pillow is of substantially uniform thickness and of generally elongated rectangular form with a relatively deep notch 10 in one lateral margin, hereinafter referred to as the front, said notch 10 being of such 10 width to freely accommodate the neck of a person therein. Preferably, the pillow also has a corresponding notch 11 in the other lateral margin, hereinafter referred to as the rear, this latter notch 11 being relatively shallow, as shown, and 15 provided for a purpose hereinafter explained. These notches 10 and 11, it will be observed, are located substantially midway between the ends of the pillow, and preferably both notches have side walls which converge to the bottom of the 20 respective notch substantially, as shown, this convergent arrangement of the side walls of the front notch 10 being particularly desirable to facilitate engagement of the person's neck therein.

By reason of these notches, the pillow comprises a neck portion 12 which extends between and connects enlarged end portions 13 which are somewhat elongated from front to rear and have the neck connection 12 thereof near the rear ends thereof. Thus the pillow has a cushion portion 14 extending forwardly a substantial distance at each side of the front notch 10 to provide adequate support for each side of a person's head when the person's neck is in the notch 10, whereas at the rear, the pillow has only a relatively slight rearwardly extending offset 15 at each end of the neck 12.

While our pillow may be made in various sizes, we have found that a pillow approximately six and one-half inches wide and approximately three and one-half inches thick is a satisfactory and convenient size. With such pillow the front notch is approximately three inches deep and five and one-half inches wide at the top and four inches wide at the bottom, and the notch 11 approximately one inch deep, seven inches wide at the top and four inches wide at the bottom.

This pillow may be made in any convenient manner, for example with top and bottom fabric pieces 16 and 17 of appropriate shape stitched at 18 to a marginal fabric band 19 of appropriate width, and forming a case or covering which is filled with any suitable cushion filling 20, such as kapok. This case may be made of a cheaper lining material with an outer slip covering of 55 similar shape applied thereover or of a material

suitably attractive for the outer covering, in which event the outer covering may be made with an opening extending across the rear and forwardly at each end of the pillow and closed with a conventional slider operated fastener, as indicated by dotted lines at 21 in Figs. 1 and 2 for convenient access for inserting and removing the filler. The filler 20 may, of course, be made of foam or sponge rubber or other similar material, molded to shape, and merely inserted in a covering with a slider fastened opening such as shown at 21.

The cushion may also be of collapsible pneumatic type, made in bladder form with a thin wall 22, as shown in Fig. 3, of rubber, plastic or the like, and fabricated so as to assume the above described pillow shape when inflated. Any conventional facilities may be employed for inflating such cushion, as for example a small collapsible tube 23 at one end which may be folded and tied at as 24 to retain the air in the cushion.

As above noted, this cushion is specially adapted for use as a neck pillow to embrace a person's neck and hold the head upright. Generally it is thus used when the person is in a sitting position in which event the pillow is placed with the rear portion against the seat back and with the person's neck in the front recess 10 and the forwardly projecting end portions 14 extending over the person's shoulders.

When thus arranged, the cushion bears against the seat back at the laterally spaced rearwardly extending offset places 15 so that the neck portion 12 of the pillow is spaced from the seat back and free to yield rearwardly under the pressure of the person's neck in the notch or recess 10.

Thus when the pillow is used as a neck pillow in sitting position, this neck portion 12 of the pillow yields and conforms somewhat to the person's neck and in so doing imparts a rocking effect to the end portions 13 of the pillow so that the forwardly projecting portions 19 thereof tend to close inwardly against the sides of the person's neck and thus insure a particularly comfortable fit against the neck and very substantial supporting of the head in upright position.

Moreover, by reason of the relatively flatwise engagement of the rear of the pillow against the seat back and the relatively wide extent of such engagement, the pillow is quite securely retained in position against the seat back and is not readily tipped or displaced from that position, and consequently provides particularly secure maintenance of the head in its pillowized position against the seat back.

By reason of its recessed contour and rear bearing arrangement this pillow is also admirably adapted, when set upright on its rear edge, to provide a cradle like cushion for supporting portions of the arms and legs. The rear bearing arrangement is such that it maintains an upright position quite readily when so used, and the notched rear form affords sufficient rocking effect on the upright end portions 14 to clamp and hold leg and arm portions quite firmly in the notch 10.

Moreover, by reason of its contour this pillow is especially appropriate for a back cushion. In such use the neck portion 12 extends across the back, for example, substantially at the waist line and affords a light comfortable cushioning at that place, while the end portions 13 extend upright

at each side of the back so that the cushioning is so distributed that the cushion is particularly appropriate and restful for a back support.

Obviously this pillow may be used for many purposes other than those particularly mentioned above, and is simple, compact, convenient and of great utility.

While we have shown and described our invention in a preferred form, we are aware that changes can be made therein without departing from the spirit of our invention, the scope of which is to be determined by the appended claims.

What is claimed is:

1. A pillow of the class described of oblong generally rectangular shape with a relatively large outwardly flared neck receiving notch at the front substantially midway between the ends of the pillow, said notch having opposed side walls which slope abruptly toward the rear of the pillow and said pillow having top and bottom faces which are substantially parallel.

2. In a pillow of the class described the combination of an outer casing and a filler, said outer casing comprising a top panel, a bottom panel, and a peripheral strip, each of said panels being of substantially rectangular shape with a corresponding truncated V-notch in one side thereof substantially midway between the respective ends thereof, said peripheral strip being secured along one margin to the periphery of the top panel and along the other margin to the periphery of the bottom panel to form the outer casing, and said filler comprising a compressible cushioning medium and being enclosed within said outer casing.

3. A pillow of the class described comprising a casing and a filler within the casing, said casing having top and bottom panels of substantially identical elongated generally rectangular shape with a deep notch in the corresponding long side of each substantially midway between the ends thereof, and a peripheral strip which extends around the pillow between said top and bottom panels and has the top and bottom margins thereof secured respectively to the margins of said top and bottom panels, said filler being a compressible medium of a shape corresponding to the interior of the casing, said peripheral strip having a slit extending lengthwise thereof from end to end of the pillow at the side thereof remote from the notches of the top and bottom panels, said slit being continued part way along each end of the pillow, and closing means extending along opposite sides of the slit and releasably connectible to close the slit.
